UNITED STATES PATENT OFFICE.

JOHN N. PEAVEY, JR., OF ASHLAND, NEW HAMPSHIRE.

CALIPERS.

SPECIFICATION forming part of Letters Patent No. 571,788, dated November 24, 1896.

Application filed May 27, 1896. Serial No. 593,200. (No model.)

To all whom it may concern:

Be it known that I, JOHN N. PEAVEY, Jr., a citizen of the United States, residing at Ashland, in the county of Grafton and State of New Hampshire, have invented certain new and useful Improvements in Calipers; and I do hereby declare the following to be a full, clear, and exact description of the invention, such as will enable others skilled in the art to which it appertains to make and use the same.

This invention relates to the pivot-joint of dividers, calipers, or like instruments, the object being to provide means whereby such instruments may be "set" to any desired measurement and firmly fixed at the joint.

The invention consists, essentially, in pivoting the legs of dividers independently to a suitable yoke and providing a rack-and-pinion mechanism connecting the legs and adjusting or controlling the same by one or more nuts threaded to a stud, as fully set forth in the following specification and claims and clearly illustrated in the accompanying drawings, forming a part of the same, of which—

Figure 1 is an elevation showing an instrument of the character above named provided with my improved joint, Fig. 2 being a broken edge view of a similar instrument provided with my improved joint. Fig. 3 is a sectional elevation showing a pair of calipers having my improved joint as when partly open. Fig. 4 is an elevation of the retaining-yoke within which the legs of dividers or calipers are pivoted. Fig. 5 is a cross-section of the same, Fig. 6 being a plan view of same. Fig. 7 is an elevation of a threaded stud within which is secured a rack for engaging the pinion-teeth with which the legs are supplied. Fig. 8 shows the threaded stud having the rack removed.

Similar reference-letters designate corresponding parts in all the views.

A represents the legs of my improved dividers or calipers, and B is a yoke-piece, in which the legs are independently pivoted by the screws or rivets C. The yoke B is also provided with a rivet or screw, as shown at c, for preventing the extreme lower edges of said yoke from springing out of place or spreading, the perforations b', which have a

central location, being formed for this purpose.

Each leg A is provided at its top with spur-teeth a', formed in a segment of a circle a, in which the leg-pivot C is concentric, and these teeth mesh with a rack D, having teeth d on each edge, said rack being rigidly secured within a slot e, formed for the purpose in the lower portion of a threaded stud E, which rests in perforation b of the yoke B, said perforation having a smooth bore, so that said stud E may be free to move longitudinally therein without being rotated, as the spur-teeth a' of the legs A rest within the slot e of the stud E, the rack D being narrower than the said stud.

Rectangular openings b² are formed one in each side of the yoke B, in which rests a nut F, which is threaded to fit the stud E, and by rotating said nut the stud is raised or lowered within the perforation b of the yoke, which causes the legs to move by engagement with the teeth of the rack D, an upward movement of the stud E causing the legs to close, and vice versa.

G is a check-nut threaded to stud E above the yoke B, which may be turned down hard onto the top of said yoke as a means of more firmly setting the joint at a given measurement after the legs A have been set, but this check-nut is by no means essential or in any way an important feature of my invention.

The top of the yoke B may be made thicker by forming a boss or hub b³ at the point where the perforation b is formed, as seen in Figs. 4 and 6, so as to provide a longer bearing for the stud E.

The yoke B is preferably provided with curvilinear end portions b⁴, whose inner surfaces correspond with the circular portion a of the top of the legs A, in which the teeth a' are formed, and a curvilinear slot a² is formed in each leg for the reception of said curved portions b⁴ of the yoke, which forms for each leg an interlocking joint and keeps out considerable dust and dirt.

The instrument may be made so as to be readily converted into either dividers or calipers by forming each leg short and providing means for connecting detachable extensions, as in the case of ordinary dividers, or the short portion of the legs may be formed partly

hollow and provided with a slot, as seen at a^3 in Fig. 2, the end of the leg being tapered slightly and provided with an external thread a^4 , to which a tapered nut H may be fitted, and after inserting either form of leg which may be required, as at A' in Fig. 3, in the socket or hollow portion of the short leg of the instrument the nut H may be turned up and thus secure the two sections A A' firmly together. In place of an extension-leg a common lead-pencil may be placed in the short leg and secured in the same manner by the nut H .

Having described my improvements, what I claim is—

1. In dividers or calipers, an adjustable joint comprising independently-pivoted legs provided with a segment of a spur-pinion within which the pivot of each is concentric, a threaded stud adapted for longitudinal movement between the pinion portions of said legs, a double rack engaging the pinions of said legs and secured to said stud, and a nut threaded to stud for adjusting the same.
2. In dividers or calipers, an adjustable joint comprising a yoke-piece carrying independently-pivoted legs provided with a seg-

ment of a spur-pinion within which the pivot of each is concentric, a threaded stud adapted for longitudinal movement between the pinion portions of said legs, a double rack engaging the pinions of said legs and secured to said stud, and a nut resting in slots formed in said yoke and threaded to said stud for adjusting the same.

3. In dividers or calipers, an adjustable joint comprising a yoke-piece carrying independently-pivoted legs having each a segment of a spur-pinion within which the pivot is concentric, a threaded stud adapted for longitudinal movement between the pinion portions of said legs, a double rack engaging the pinions of said legs and secured to said stud, and a pair of nuts threaded to said stud one resting in slots formed for the purpose in the yoke and the other placed above and adapted to be turned down upon said yoke, all substantially for the purpose set forth.

In testimony whereof I affix my signature in presence of two witnesses.

JOHN N. PEAVEY, JR.
